(57) **CLAIM**

I claim the ornamental design for a cargo box with double bevel lid, as shown and described.

DESCRIPTION

FIG. 1 is a perspective view of a cargo box with double bevel lid;

FIG. 2 is a top plan view thereof;

FIG. 3 is a front elevational view thereof;

FIG. 4 is a left side elevational view thereof;

FIG. 5 is a bottom plan view thereof;

FIG. 6 is a rear elevational view thereof;

FIG. 7 is a detail left side elevational view of a corner thereof; and,

FIG. 8 is a detail top perspective view of a corner thereof. The right side of the cargo box with double bevel lid is a mirror image of the left side, and is therefore not shown. The four corners of the lid of the design are identical, and so only one is shown.
